UNITED STATES PATENT OFFICE.

ALBERT R. TIFFANY, OF DAYTON, OHIO, ASSIGNOR OF FIVE-SIXTHS TO
MICHAEL NEIL, HORACE L. GILLETTE, AND JOHN J. LELAND, ALL OF
SAME PLACE.

SCREW-JACK.

SPECIFICATION forming part of Letters Patent No. 295,838, dated March 25, 1884.

Application filed January 26, 1884. (No model.)

To all whom it may concern:

Be it known that I, ALBERT R. TIFFANY, of Dayton, in the county of Montgomery and State of Ohio, have invented certain new and useful Improvements in Screw-Jacks; and I do hereby declare the following to be a full, clear, and exact description of the same, reference being had to the accompanying drawings, forming a part of this specification, and to the figures and letters of reference marked thereon.

My improvement will be first described in connection with the accompanying drawings, and will then be pointed out particularly in the claims at the end of this specification.

15 In said drawings, Figure 1 represents a side elevation of a screw-jack constructed in accordance with my invention; Fig. 2, a longitudinal vertical section of the same; Fig. 3, a horizontal section taken on the line $\alpha\alpha$, Fig. 20 1. Fig. 4 is a view showing the hub carrying the worm-wheel and ratchet. Fig. 5 is a perspective view of the two-part nut in which the main screw-shaft works.

Similar letters of reference in the several 25 figures indicate the same parts.

The letter A designates the standard of the jack, in or upon which the various working parts are mounted.

30 B is the main screw-shaft, carrying at its upper end a rotatable head, C, constructed and applied in any suitable manner.

D is a screw-nut divided centrally and vertically into two parts, and having vertical side walls and inclined end walls, d d, which work 35 against the correspondingly-shaped inner faces of the standard A, as shown in Fig. 2. I term this nut a "gravitating nut," from the fact that its parts, from their weight and the inclination of their ends, automatically drop down 40 and crowd together and into engagement with the main screw-shaft. Each of the parts of the gravitating nut is provided with an inclined groove, e, into which projects a corresponding inclined rib, f, formed upon the wall 45 of the standard, from which it results that when the nut is raised its parts are caused to separate and assume the position shown in dotted lines, Fig. 2. A loose key, g, is inserted in corresponding horizontal grooves in the sides 50 of both the nut-sections, for the purpose of

keeping the parts of the nut always in the same horizontal plane and preventing them from rising or falling unequally. The normal position of the nut is preserved by the mere weight of its parts; but to raise it I provide a foot-lever, H, pivoted at the base of the standard and connected by separate rods, h h, to the respective sections. When the foot-lever is depressed, the nut-sections are raised and caused to spread apart by reason of their 55 fixed and positively-acting inclined guides until finally they are entirely released from engagement with the screw-shaft, in which position they allow said shaft to drop down to its lowest position.

60 The means employed for raising the screw-shaft consist, briefly, of a hub, I, having at its lower end a worm-wheel, J, with which meshes a worm, J', on a shaft, J², and having at its upper end a ratchet, K, with which operates a pawl, l, carried by a vibrating handle, L. This hub I has a smooth bore and fits upon the screw-shaft B, and is provided with a feather or tongue, i, which enters a longitudinal groove, b, in the shaft, and which, 65 while it permits the shaft to be freely adjusted up and down without disturbing the hub, causes any rotary movement of the hub to be imparted to the shaft, so as to raise or lower it. The end of the shaft J² is provided with a ratchet-wheel, M, with which engages a pawl, N, carried by a vibrating arm, O. The shaft J² is preferably mounted in adjustable bearings P P, which permit it to be adjusted in and out, so as to cause its worm J' to engage 70 with or disengage from the worm-wheel J at pleasure. The pawls l and N and their respective ratchets are preferably arranged so as to be worked either to the right or to the left, as will be readily understood. When it 75 is desired to move with the jack a moderate weight only, the worm J' is adjusted back out of engagement, and the hub I is rotated by the action of the hand-lever L, pawl l, and ratchet k, and by its rotation causes the screw-shaft 80 to be turned in the gravitating nut and to be raised or lowered with a comparatively rapid motion, according to the direction of rotation; but when a very heavy weight is to be moved, 85 requiring the application of greater power, and 90

consequent slower motion of the shaft, the worm J' is adjusted inward and rotated by power applied to the hand-lever O, and through the instrumentality of the gear J causes the hub I, and consequently the main screw-shaft, to rise or descend with a slower but more powerful movement. The provision of the gravitating nut and the means for raising it is very convenient, as it enables the screw-shaft to be shifted instantly from a lower to a higher or from a higher to a lower elevation without the intervention of the more slowly acting rotary hub. For instance, by pressing the foot on the treadle when the shaft 15 is at its lowest point of adjustment, the gravitating nut can be freed from the shaft B, and the latter be drawn instantly to a higher elevation and there maintained by simply releasing the treadle and allowing the gravitating nut to fall; or if it is desired to lower the screw 20 from a higher elevation, it can be automatically accomplished by pressing on the treadle till the nut is relieved of the shaft, when the latter will drop automatically of its own weight.

25 It will be observed that the standard or casing of my jack is so constructed as to entirely inclose the operative parts of the device and prevent access to the same of water, snow, ice, sand, dirt, or anything else which would tend 30 to injure or clog them and impair their action. This feature I deem of much practical importance.

I claim as my invention—

1. In a screw-jack, the combination of a screw-shaft and a divided gravitating nut having inclined ends with a standard or case having inclined bearing-faces for the ends of the nut to work against, substantially as described.
- 40 2. In a screw-jack, the combination of a screw-shaft, a divided gravitating nut having inclined ends, and fixed and positively-acting guides for opening and closing the parts of the nut, with a standard or case having inclined bearing-faces for the ends of the gravitating nut to work against, substantially as described.
- 45 3. In a screw-jack, the combination, with the screw-shaft, of a divided gravitating nut, guides for positively opening and closing it, and means for keeping its parts in the same

horizontal plane at all points of adjustment, substantially as described.

4. In a screw-jack, the combination of a screw-shaft with a divided gravitating nut having inclined ends, a standard or casing 55 having inclined bearing-faces for the ends of the gravitating nut to work against, and means for raising the nut, substantially as described.

5. In a screw-jack, the combination, with the screw-shaft, of a divided nut, the parts of 60 which gravitate toward the screw-shaft, guides for said nut, and a lever and connections for raising it, substantially as described.

6. In a screw-jack, the combination, with the screw-shaft, of the divided nut whose parts 65 gravitate toward the screw-shaft, operating-treadle pivoted to the base of the jack, and connections for raising the nut by the operation of the treadle, substantially as described.

7. In a screw-jack, the combination, with the screw-shaft, of the elongated hub having the feather projecting into the groove in the shaft, and having also the worm-gear and the ratchet at opposite ends for the application of 75 the worm and the pawl-arm, respectively, substantially as described.

8. In a screw-jack, the combination, with the screw-shaft, of the divided gravitating nut and its guides, the elongated hub acting upon 80 the shaft, and means for rotating said hub, substantially as described.

9. In a screw-jack, the combination, with the screw-shaft, of the divided gravitating nut and its guides, the elongated hub having the worm-gear, with the worm for engaging with 85 the worm-gear, and the means for adjusting the said worm into or out of engagement, substantially as described.

10. In a screw-jack, the combination, with the screw-shaft, of the divided gravitating nut 90 and its guides, the elongated hub having the upper ratchet and the lower worm-gear, the upper lever and its pawl, and the adjustable worm and means for operating it, substantially as described.

ALBERT R. TIFFANY.
